UNITED STATES PATENT OFFICE.

JOHN J. COOKE, OF CHERRY VALLEY, NEW YORK.

TREADLE-POWER.

SPECIFICATION forming part of Letters Patent No. 731,863, dated June 23, 1903.

Application filed November 15, 1902. Serial No. 131,541. (No model.)

To all whom it may concern.

Be it known that I, JOHN J. COOKE, a citizen of the United States, residing at Cherry Valley, in the county of Otsego and State of New York, have invented new and useful Improvements in Treadle-Powers, of which the following is a specification.

My invention has relation to improvements in treadle-powers; and the object is to provide an improved and simplified mechanism of the kind named and for the purposes where such mechanism may be advantageously used.

The invention embodies a support, a treadle, a spring to lift the treadle, a crank having one arm longer than the other, a connection between the crank and the treadle, a rod slidably connected to the longer arm of the crank, and a bracket slidably and adjustably secured to said rod and adapted to be connected to a revolute member, all as hereinafter fully described and the novelty thereof particularly pointed out and distinctly claimed.

It will be premised that while I have illustrated the device as operatively connected to a cream-separator it is apparent that it may with equal adaptability be utilized whenever a reciprocating movement is used to produce a rotary motion.

I have fully and clearly illustrated my invention in the accompanying drawings, forming a part of this specification, and wherein—

Figure 1 is a perspective view of the complete device, showing it as associated with a cream-separator. Fig. 2 is a side view of the bracket by which the reciprocating pitman is supported. Fig. 3 is a perspective view showing a double crank, used as the operating means.

In the drawings like reference notations appearing in the different illustrations denote the same parts.

Referring to the drawings, A designates a cream-separator of any selected and approved make having a rotary shaft, the end of which is projected from the casing, as shown.

1 designates a double-inclined supporting-bench, in the apex of which is formed a bearing-sleeve 2, wherein is pivotally posited a crank-shaft 3, to the free end of the arm of which is pivotally connected the upper end of the treadle pitman or rod 4. To the base

of one of the legs of the bench is pivotally secured one end of the treadle 5, the other end being suitably connected to the lower end of 55 the pitman 4. A foot-piece 6 extends from the treadle-bar, as shown. A contractile spring 7 is provided to lift the treadle, having one end fixed to the leg of the bench and its lower end secured to the treadle, so that when 60 the treadle is depressed and the force removed the spring will raise it. To the inner end of the crank-shaft is secured an arm 8, made longer than the crank-arm and formed with an elongated slot 9, wherein a wrist-pin 10 is 65 slidably secured. To the pin 10 is pivotally secured the lower end of a pitman-rod 11, the upper end portion of which is slidably and adjustably arranged in a sleeve or passage in a bracket 12, substantially as shown in the 70 drawings. A set-screw 13 is provided to hold the bracket in any position to which it may be placed on the pitman. The bracket 12 is formed with an overhanging ear 14 and a pivotally-supported jaw 15, having a perforated and threaded lug 16, which takes in a clamping-screw 17, passed through a lug 18 on the end of the arm 14, whereby the bracket may be clamped to the handle 19 of the crank-arm of the cream-separator, substantially as 75 80 shown in the drawings.

In Fig. 3 of the drawings is illustrated the device provided with a double crank-shaft *a* and treadles *b c*, supported on the wrists of the cranks, as shown. In other respects the 85 construction is identical with that of Fig. 1.

The operation is readily ascertained from the foregoing description, taken in connection with the drawings. Upon operating the treadle the crank, with the arm 8 and the pitman 11, is reciprocated and the arm 19 revolved.

Having thus fully described the invention, what is claimed as new is—

1. A treadle-power, comprising a double-inclined supporting-bench formed with a bearing in its apex, a treadle pivotally mounted to one of the legs of the bench, a crank journaled in the bearing in the apex of the bench, a connecting-rod pivotally secured to the free end of the crank-arm and its other end secured to the treadle, a spring to lift the treadle, an arm longer than the crank rigidly secured to the crank-shaft and formed

with an elongated slot in its outer portion, and a rod having its lower end slidingly secured in the said slot and its upper end adjustably secured to a rotatable member.

- 5 2. A treadle-power, comprising a double-inclined supporting-bench formed with a bearing in its apex, a treadle pivotally mounted to one of the legs of the bench, a crank journaled in the bearing in the apex of the 10 bench, a connecting-rod pivotally secured to the free end of the crank-arm and its other end secured to the treadle, a spring to lift the treadle, an arm longer than the crank

rigidly secured to the crank-shaft and formed with an elongated slot in its outer portion, a 15 rod having its lower end slidingly secured in the said slot, a bracket adjustably secured to the upper end of said rod, and a revoluble member adjustably projected and secured in the bracket. 20

In testimony whereof I affix my signature in presence of two witnesses.

JOHN J. COOKE.
